United States Patent Office

Des. 231,579
Patented Apr. 30, 1974

231,579

SAFETY RAZOR

John F. De Lorenzo, Washington, D.C., assignor to
Tica Industries, Limited, Baltimore, Md.

Filed Sept. 26, 1972, Ser. No. 292,408

Term of patent 14 years

Int. Cl. D28—03

U.S. Cl. D95—3 A

FIG. 1

FIG. 2

FIG. 3

FIG. 6

FIG. 4

FIG. 5

FIG. 1 is a front perspective view of a safety razor showing my new design;

FIG. 2 is a right side elevational view;

FIG. 3 is a rear elevational view;

FIG. 4 is a top plan view thereof;

FIG. 5 is a bottom plan view thereof; and

FIG. 6 is a perspective view of a safety razor showing a modified form of my new design.

I claim:

The ornamental design for a safety razor, substantially as shown and described.
